United States Patent Office

Des. 209,061
Patented Oct. 31, 1967

209,061

STATUETTE OR THE LIKE

Andrew Latzko, 24½ Main St.,
Luzerne, Pa. 18709

Filed July 20, 1964, Ser. No. 80,923

Term of patent 14 years

(Cl. D29—23)

FIG. 1 is a front elevational view of the statuette embodying my new design.

I claim:

The ornamental design for a statuette or the like, as shown.
